CLAIM

I claim the ornamental design for a bottle of liquid solutions for electronic cigarettes, as shown and described.

DESCRIPTION

FIG. 1 is a front-side perspective view of a bottle of liquid solutions for electronic cigarettes showing my design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines shown represent unclaimed subject matter and form no part of the claimed design.

1 Claim, 6 Drawing Sheets
